UNITED STATES PATENT OFFICE.

FRANK C. HUTCHISON, OF MINNEAPOLIS, MINNESOTA.

VARIOMETER FOR WIRELESS RECEIVING SETS.

Application filed June 15, 1922. Serial No. 568,454.

My invention has for its particular object the provision of an improved electromagnet tuning instrument for wireless receiving sets, said tuning instrument being of the 5 type generally designated as a "variometer". As is known, a variometer is a type of tuning coil in which a plurality of coils connected in series are rotatably mounted for adjustments to thereby vary 10 the relative positions of the north and south poles of said magnets. It is also known that such adjustments of the magnets in respect to the relative positions of the north and south poles, would serve to tune the 15 receiving set for different wave lengths.

In the hitherto commercial variometer, one coil called the "rotor" has been mounted for angular rotary adjustments within the other coil called the "stator", 20 and each of said coils has had a large number of convolutions or turns. When two variometer coils are positioned with the north end of one at the south end of the other, the total magnetism of the two will 25 be zero, while if they are turned with their north poles in the same direction and their south poles in the same direction, the magnetism of the one will assist the magnetism of the other. These conditions are utilized 30 in tuning because, other things being equal, the stronger the magnetism about the tuning coil, the greater will be the wave length to which it will respond.

In the commercial variometer, both of the 35 coils have customarily been given a large number of turns so as to give the instrument the desired and necessary range of adjustment in tuning, but it has followed that in such arrangements there has been great difficulty in obtaining the desired close adjustments so that, frequently, it has been impossible to keep the variometer from passing the position for the selection of the required wave length and, for that reason, it 40 has been frequently impossible to "tune in".

My invention remedies the above defect and consists in the provision of a differential multiple variometer. More definitely

stated, the complete variometer involves two pairs of variometer coils connected in series, the one pair of coils having a relatively very large number of turns serving to adjust for range and the other pair of coils having a relatively very small number of turns and 55 serving to adjust for extreme accuracy or what may be termed "micrometer degree of variation of wave length". In carrying this invention into commercial form, I provide three spools, the first of which is fixed, 60 the second of which is mounted to rotate within the first and the third of which is mounted to rotate within the second; the main variometer coils are wound, one on the interior of the fixed first spool and the other 65 on the exterior of the rotary second spool, while the auxiliary coils are wound, one within the rotary second spool and the other on the exterior of the third and relatively small rotatably mounted interior spool. 70

With the above general statements made, I will now describe more in detail a commercial embodiment of my invention, which is illustrated in the accompanying drawings, wherein like characters indicate like 75 parts throughout the several views.

Referring to the drawings:

Fig. 1 is a front elevation showing the dials and operating knobs, which may be and preferably are used in connection with 80 my improved variometer;

Fig. 2 is a view partly in elevation and partly in vertical section on the line 2—2 of Fig. 1, showing the improved variometer;

Fig. 3 is a horizontal section taken approximately on the line 3—3 of Fig. 2, some parts being shown in full;

Fig. 4 is a vertical section taken on the line 4—4 of Fig. 3;

Fig. 5 is a diagrammatic view illustrating 90 the wiring of the improved variometer and its connection to a wireless receiving set of well known commercial form; and

Fig. 6 is a fragmentary horizontal section illustrating a slightly modified form of the 95 improved variometer.

Referring first to the construction illustrated in Figs. 1 to 5, inclusive, the numeral

7 indicates the first or fixed outer spool, the numeral 8 indicates the second or relatively large rotary spool and the numeral 9 indicates the third or small interior spool, 5 which spools are made of non-conductive and non-magnetic material, such as wood. The spool 7 is formed with an internal spherical surface, against which the stationary member 10 of the main variometer coils 10 is secured in the customary way. The spool 8 has a spherical outer surface on which the movable variometer coil 11 is secured, also in the customary way. In carrying out my invention, the spool 8 is formed with 15 a hollow spherical inner surface 12 to which the relatively fixed auxiliary variometer coil 13 is secured. The small inner spool 9 has a spherical outer surface on which the relatively movable auxiliary variometer coil 14 is secured. With the above arrangement, the coils 10 and 11 are spaced but closely positioned and the auxiliary coils 13 and 14 are also spaced but closely positioned.

The main spool 8 is provided with axially 20 aligned outwardly projecting tubular shafts 15 and 15^a, which, as shown, are journaled in bearing plates 16 secured to the opposite sides of the fixed spool 7. The shaft 15 is also shown as journaled in one side of a 25 casing 17 and secured to the outer end thereof is a dial 18 and a main operating knob 19. The small inner spool 9 is secured to axially spaced but axially aligned small shafts 20 and 20^a that extend through and 30 are journaled in the shafts 15 and 15^a, respectively. The shaft 20, at its outer end, is provided with a relatively small so-called auxiliary knob 21. Adjustments of the spool 8 are, of course, made by manipulation of 35 the main knob 19, and adjustments of the small inner spool 9 are made by manipulation of the auxiliary knob 21. In the preferred arrangement, the dial 18 is provided with a light spring 22 that frictionally 40 engages the plate 17 and serves to prevent the spool 8 from being accidentally moved or from being moved when the inner spool 9 is adjusted. The secondary knob 21 is also preferably provided with a spring 45 finger 23 that frictionally engages the adjacent end of the main knob 19 and produces sufficient friction to cause the inner spool 9 to normally move with the spool 8. The spring finger 23 is also preferably 50 used as a pointer for cooperation with a dial or graduations 24 marked on the end of the knob 19.

As already stated, the coils 10, 11, 13 and 55 14 are connected in series and, as shown, this is accomplished as follows: The numerals 25 and 26 indicate the direct current leads of the wireless receiving set. The lead 25 is connected to one terminal 10^a of the main coil 10 and the other terminal 10^b of said coil is connected to the tubular

shaft 15^a. Said shaft 15^a, at its inner and outer ends, is provided with insulating portions 15' that directly engage the shaft 20^a but electrically insulate the two shafts, one from the other. The tubular shaft 15^a, 70 near its inner portion, is electrically connected to one terminal 11^a of the relatively movable main coil 11, and the other terminal 11^b of said coil 11 is connected to one terminal of the auxiliary coil 13, the other terminal 13' of which coil 13 is electrically connected to the tubular shaft 15, (see Fig. 3). The shaft 20 is electrically connected to the shaft 15 and its inner extremity is electrically connected to one terminal 14^a 80 of the auxiliary coil 14, the other terminal 14^b of said coil 14 being electrically connected to the shaft 20^a. The outer end of said shaft 20^a is connected by a wire 27 to the lead 26. The wires 10^b and 27 have sufficient slack to permit complete oscillatory rotations of the spools 8 and 9 in respect to each other and in respect to the fixed spool 7. All of the wires noted are covered 85 with suitable insulation.

The construction illustrated in Fig. 6 differs from that above described only in the fact that the inner surfaces of the fixed spool 7' and of the adjustable spool 8' are 90 cylindrical. This construction does not give as high efficiency as the spherical construction above described, but has the advantage that said spools do not need to be made in sections but can be made each of an integral member.

In the arrangement above described, it is evident that the several coils 10, 11, 13 and 14 are always connected in series, regardless of adjustments. It is also evident that, by manipulation of the knob 19, the instrument may be quickly brought approximately into tune in the customary way and that the final accurate adjustment may be made by manipulation of the auxiliary knob 21, which imparts movements to the small inner spool 9 and the coil carried thereby. In practice, it will frequently happen that in adjusting for tuning by manipulation of the knob 19, there will be a clicking or sound indication indicating that the adjustment has just passed the proper tuning pitch and, when this takes place, the main knob should be stopped or set and the final selecting adjustment should be made by manipulation of the knob 21.

In actual practice, I have found this improved tuning instrument or differential variometer to be highly satisfactory for the purposes had in view and to make the most accurate tuning adjustments an exceedingly easy matter. The manner in which the main and auxiliary coils, which make up the differential variometer, are assembled together, not only brings them into the most compact form but makes it feasible to asso- 125 130

ciate the main and auxiliary knobs in such close proximity that they may be operated by one hand and approximately as a single knob.

5 What I claim is:

A differential variometer comprising a fixed outer main spool, a cooperating hollow main spool rotatably mounted within said fixed spool, a relatively small auxiliary spool rotatably mounted in said rotary main spool, cooperating main variometer coils se-

cured one to the interior of said fixed main spool and the other to the exterior of said rotary main spool, and auxiliary variometer coils of relatively low inductance secured one to the interior of said rotary main spool and the other to the exterior of said inner auxiliary spool, the said coils being connected in series.

In testimony whereof I affix my signature.

FRANK C. HUTCHISON.
